UNITED STATES PATENT OFFICE.

JAMES SCOTT MILLER AND WALTER MILLER, OF BEAVER FALLS, PENNSYLVANIA.

DETACHABLE CUFF FOR TROUSERS.

1,023,864.

Specification of Letters Patent. Patented Apr. 23, 1912.

Application filed September 27, 1911. Serial No. 651,579.

To all whom it may concern:

Be it known that we, JAMES SCOTT MILLER and WALTER MILLER, residents of Beaver Falls, in the county of Beaver and State 5 of Pennsylvania, have invented a new and useful Improvement in Detachable Cuffs for Trouzers, of which the following is a full, clear, and exact description, reference being had to the accompanying drawings, forming 10 part of this specification, in which—

Figure 1 is a side elevation partially in section of the bottom of the leg of a pair of trousers, showing one form of my improved cuff attached thereto. Fig. 2 is a 15 vertical section through the cuff shown in Fig. 1, and Fig. 3 is a perspective view of a cuff in which I have shown a modified form of an attaching device.

This invention relates to cuffs for trousers; and is designed to provide a cuff of 20 this character which can readily be attached to and detached from the bottom of the leg of a pair of trousers having the regular cut, and which will give them the appearance 25 of trousers having properly shaped cuffs formed integrally therewith.

Our invention comprises a continuous 30 cuff for trousers which is fastened to the trousers' leg by means extending to the inside of said trousers' leg; it being understood, however, that changes may be made 35 in the details of construction of the cuffs as well as the devices for attaching the cuff to the trousers, without departing from the spirit and scope of our invention as defined in the appended claims.

In the drawings referring to the form of 40 Figs. 1 and 2, in which we show one form of our invention the numeral 2 designates the leg of a pair of trousers which have 45 been properly shaped at the bottom to be worn without a cuff. The continuous cuff is made of the same material from which the trousers are made and is provided with 50 an outer fold 3 and an inner fold 4 which is turned upwardly at the bottom 5, thereby forming a space between these folds which is arranged to receive the bottom of the leg 2. The inner face of the leg 2 is provided 55 with a series of eyes 6 which are arranged to be engaged by hooks 7 connected to the inner face of the inner fold 4 of the cuff.

In Fig. 3 we have shown a cuff similar 60 to that shown in Figs. 1 and 2, but which is provided with tapes or webs 8 attached 65 to the inner face of the fold 4. These tapes 70

are provided with hooks 7^a at the upper ends which are arranged to engage eyes 75 secured to the inside of the bottom of the leg of the trousers.

We are aware that it is old to provide trousers with cuffs which have been formed integrally therewith, and which have been 80 properly shaped to prevent wrinkling of the trousers at the upper end of the cuff. 85 The disadvantage of this arrangement, and particularly in ready made clothing, arises when the trousers have to be shortened to suit the wearer. As the leg of the trousers is cut on a taper it involves considerable 90 work to shorten the leg and at the same time properly shape the cuff and the bottom of the leg to prevent wrinkling. We are also aware that trousers have been made in 95 which the bottom of the leg is turned up to form the cuff, and when the wearer desires to use them without the cuff, they are turned back to the initial position. This arrangement is very unsatisfactory, as the bottom of the leg is considerably smaller 100 in diameter than a point several inches above the bottom to which the bottom is brought when it is turned upwardly to form the cuffs and when the bottom is turned upwardly, it will naturally wrinkle the leg 105 of the trousers at the top of the cuff.

The advantages of our invention result from the provision of a cuff which can be properly cut and shaped from its own pattern, and which can readily be attached to 110 and detached from the bottom of the leg of a pair of trousers which have been properly shaped. Another advantage results from the provision of a cuff which is properly shaped to fit the bottom of the leg, 115 and if the trousers must be shortened to suit the wearer, the bottoms can be readily bushed to properly fit the cuff, and therefore the wearer will obtain a pair of trousers in which the bottoms of the legs have been 120 properly shaped, even though they have been shortened. A further advantage is that the cuff, when worn, acts as a protection or guard for the edge of the trousers legs and prevents it from wearing or becoming soiled.

We do not limit ourselves to the employment of hooks and eyes as the fastening or attaching means for the cuff, since any convenient form of fastening devices may 125 be employed. The cuff may also be varied in size, shape, &c., without departing from

our invention. It may also be of single thickness or folded back as shown. It will also be understood by those familiar with the art, that our invention can be successfully used in connection with the sleeves of coats.

We claim:

1. A continuous cuff for trousers or the like, having fastening devices arranged to engage coöperating fastening devices on the inside of the trousers' leg; substantially as described.
- 10 2. A continuous cuff for trousers, having shaped inner and outer folds, there being

a space between the folds arranged to receive the bottom of a leg of a pair of trousers, and fastening devices connected to the inside of the inner fold arranged to engage coöperating fastening devices on the inside of the leg; substantially as described. 15 20

In testimony whereof, we have hereunto set our hands.

JAMES SCOTT MILLER.
WALTER MILLER.
